ARTIFICIAL SILK DRY SPINNING APPARATUS

James J. Calhoun, Waynesboro, Va., assignor to
E. I. du Pont de Nemours & Company, Wil-
mington, Del., a corporation of Delaware

Application December 18, 1941, Serial No. 423,554

1 Claim. (Cl. 18—8)

This invention relates to new and improved apparatus for application to spinning cells used in the dry or evaporative method of spinning artificial filaments. More particularly the invention relates to new and improved apparatus for introducing air or other evaporative medium immediately adjacent the face of the spinneret in the spinning cell.

The manner in which solvent is removed from gel filaments of cellulose acetate yarn or the like formed by the evaporative spinning method within the first few inches of travel from the spinneret face is all important in determining the characteristics of the yarn formed. In a modern cellulose acetate spinning plant, spinning speeds are relatively high and the yarn travels through this critical distance in about one one-hundredth of a second. Furthermore, in order to get uniformity of results and continuity of spinning, each and every filament comprising the yarn should be subjected to the same conditions of initial drying or evaporation of solvent. Moreover, for economy of operation, it is important that the evaporative medium exhausted from the spinning cell and passed to the solvent recovery system be rich in solvent vapors. Yet on the other hand, air heavily laden with solvent vapors is of little value in evaporating more solvent from the yarn. It is, therefore, important to present evaporative medium relatively free from solvent vapors to each of the filaments issuing from the spinneret and at the same time to use this evaporative medium in a highly efficient manner, that is, use a relatively small quantity to pick up the maximum allowable amount of solvent.

This essential uniform and efficient circulation of air or other evaporative medium about the various filaments of the bundle in close proximity to the spinneret is satisfactorily achieved by the vane door described in the Williams application, Serial No. 306,649 filed November 29, 1939, U. S. P. 2,285,245, but the location of the radial vanes about a central point immediately opposite the face of the spinneret makes it impossible for the operator to view the filaments coming from the spinneret; hence slow holes or plugged holes in the spinneret cannot readily be detected.

An object of this invention, therefore, is to provide simple means for uniformly and efficiently circulating air or other evaporative medium about the individual filaments issuing from the spinneret in the head of a dry spinning cell, integrally coupled with means for visually inspecting the zone immediately adjacent the face of the spinneret.

Another object is to provide an improved door or closure member assembly for the head of the spinning cell whereby air or other evaporative medium can be introduced into the cell in a turbulent form and, at the same time, permit the operator to view the spinning without removing the door or otherwise upsetting the spinning equilibrium.

These and other objects will more clearly appear from the description which follows:

Briefly stated, my invention comprises a door or closure member adapted to cover a complementary opening in the side-wall of the spinning cell closely adjacent the spinneret; the door or closure member being provided with a sight opening covered with glass or other transparent material not affected by the solvent vapor in the cell, and located to permit usual inspection of the zone about the face of the spinneret, a cooperating light opening located to permit illumination of the zone about the face of the spinneret, and around the sight opening a plurality of air-directing slots through which air or other evaporative medium is introduced into the cell in turbulent form.

The details of my invention are set out in the following description, reference being had to the accompanying drawing wherein

Fig. 1 is a front elevation of a preferred form of the invention;

Fig. 2 is a cross-sectional view on the line A—A of Fig. 1;

Fig. 3 is a cross-section on the line B—B of Fig. 1 and shows in detail the construction of an air-inlet opening;

Fig. 4 is a front elevation of a modified form of construction;

Fig. 5 is a detail view of an alternate construction of light-opening; and

Fig. 6 is a cross-section on the line A—A of Fig. 5.

In a preferred embodiment of my invention, illustrated in Figs. 1, 2 and 3, the door or closure member is comprised of a panel 1 of appreciable thickness, which may be provided with any convenient means (not shown) of mounting the same in the side wall of the spinning cell, and over the complementary opening provided therefor. Centrally located with respect to the vertical axis of panel 1 is a sight-opening, preferably circular, provided with a glass retaining flange 2 adjacent the one face of the panel and a recessed portion 3 adapted to receive a snap wire glass retaining ring 4, adjacent the opposite face of the panel. 55 A pane 5 of glass or other transparent material

which is not affected by the solvent vapor is held in position by the flange 2 and snap-wire ring 4. Directly below the sight opening is a smaller funnel-shaped light-directing opening 6 which serves to direct a beam of light, from a flash-light or other convenient source, generally on or near the face of the spinneret. To either side of light-directing opening 6, and below the sight opening are relatively long air-inlet slots 7 which extend radially with respect to the center of the sight opening. Additional and relatively short air-inlet slots 8 are located on either side of the sight opening and likewise extend radially with respect to the center of the sight-opening. Preferably slots 7 and 8 are centered 30° apart with one pair of the slots being centered on the horizontal axis of the sight-opening. All of the air-inlet openings slope at an angle, preferably of 30°, to the plane of the face of panel 1, as shown in Fig. 3.

This arrangement gives very good turbulence and excellent spinning under normal conditions when only one yarn is formed per spinneret and for the spinning of a single yarn from one spinneret this form of the invention is preferred.

In the modification shown in Fig. 4, the short air-inlet slots 8' are centered on, but have their longer axis at right angles to, the radial lines passing through the center of the sight-opening.

This modified arrangement of the slots, through which air is introduced into the spinning cell, is especially desirable for double end spinning, i. e., the spinning of two threads from a single spinneret, inasmuch as the small side slots divert the incoming air around the sides of the cell-head and thus prevent the filaments of the divided yarns from striking the cell walls.

In place of the funnel-shaped light-directing opening (Fig. 2) I may employ the construction illustrated in Figs. 5 and 6 wherein the opening is a slot of wedge-shaped cross-section, the apex of the wedge being at the outer face, and the base of the wedge being at the inner face of panel 1.

It is to be understood, of course, that my invention is not limited to the precise details of construction recited above, which are for purposes of illustration only, but is susceptible rather to a wide variation of arrangement and the substitution of obvious mechanical equivalents. Thus, instead of a relatively thick panel portion, the closure may be made of sheet metal or the

like, and air-deflecting ears or flaps may be substituted for the sloped slots of the preferred embodiment described. Furthermore, the panel need not be separate from the cell but may be made integral therewith by modifying the cell side-wall at the appropriate point in accordance with the spirit of my invention. Finally the glass or other transparent material may be maintained in position by any one of a number of obvious 10 mechanical expedients. The only essential requirement is that the general organization of sight-, light- and air-inlet openings disclosed herein be observed.

By use of my invention, the operator can shine 15 a light through the window and readily determine whether or not all the holes in the spinneret are free and passing their portion of the spinning solution, and at the same time there is made possible the introduction of the evaporative 20 medium into the cell with the desired turbulence.

I claim:

In an evaporative spinning apparatus comprising 25 a spinning cell having a spinneret within the upper portion thereof, arranged for double end spinning, the improvement which comprises a relatively thick closure member adapted to cover a complementary opening in the side wall of the cell closely adjacent the spinneret, said closure member being provided with a circular 30 sight-opening covered with transparent material, a light-opening directly therebelow, and a plurality of air-inlet openings disposed in a circle about said sight-opening, said air-inlet openings comprising two relatively long slots located 35 below the sight-opening and extending radially with respect to the center of the sight-opening and at an angle of 30° from the vertical axis of the sight-opening, and a plurality of shorter slots extending at right angles to radial lines 40 from the center of the sight-opening and located above said long slots and to each side of the sight-opening, each of said slots extending thru the relatively thick closure member at an angle of 30° with respect to the face of said closure 45 member and toward the adjacent wall of the spinning cell whereby evaporative medium entering the cell thru said slots is directed around the walls of the spinning cell.
